UNITED STATES PATENT OFFICE.

JOHN MANOFSKY, OF WARREN, OHIO, ASSIGNOR TO YOUNGSTOWN PRESSED STEEL COMPANY, OF WARREN, OHIO, A CORPORATION OF OHIO.

EXPANDED METAL LATH.

Application filed June 21, 1926. Serial No. 117,401.

This invention relates to expanded metal lath and is fully described in the following specification and shown in the accompanying drawings in which Figure 1 is a front elevation of a section of a lath embodying the invention showing the same partly covered with plaster and Fig. 2 is a vertical section through the same.

The embodiment illustrated comprises an expanded lath having a plurality of rows of herringbone construction separated by longitudinal portions 10 which are horizontally disposed. The sheet metal blank is slotted and expanded in a well-known manner to produce the herringbone lath, having a series of strands 11 separated by slots 12. These strands will meet in a central strip 13, the outer ends being integral with edge strips 14 which form part of the longitudinal portions or ribs 10.

The central strip 13 and the edge strips 14, as will be seen in Fig. 2, lie in planes which are substantially parallel to each other and which are nearly at right angles 25 to the front edges of the strands 11 when viewed edgewise, as in Fig. 2.

Thus, it will be seen that the longitudinal portions 10, together with the edge strips 14, form substantially a Z-shaped rib and 30 that the strands 11 extend in nearly opposite directions from the center strips 14. This permits the strands to bend naturally and easily without placing them under any undue strain or twist and helps materially 35 in expanding the lath.

When used as lath which is to receive plaster, the sections are placed horizontally with the center strips 13 lying back of the strands 11 immediately above it in such a way as to form a ledge which will serve to 40 support the mortar, as at A in Fig. 2. Likewise the uppermost edge strip 14 will also serve to hold the mortar, as at B.

Another marked advantage of this lath 45 is that for a given weight of metal it is very rigid, the longitudinal ribs 10 being of Z-shaped cross section adding very greatly to the stiffness of the construction.

While I have shown and described but a 50 single embodiment of my invention, it is to be understood that it is capable of many modifications. Changes, therefore, in the construction and arrangement may be made which do not depart from the spirit and

scope of the invention as disclosed in the appended claims.

I. Claim:

1. An expanded metal lath having a plurality of rows of herring-bone construction, a row having at one side a central strip, and longitudinal portions of Z-shaped cross-section, the flanges of said Z-shaped portion forming ends for the strands, said strips and flanges lying in substantially parallel planes at an angle to the plane of the lath 60 so as to form ledges to support mortar pressed through the spaces between strands when the strips are horizontal.

2. An expanded metal lath having a plurality of rows of herring-bone construction, each row having a central strip, and longitudinal portions of Z-shaped cross-section, the flanges of said Z-shaped portion forming ends for the strands, said strips and flanges 70 lying in substantially parallel planes at an angle to the plane of the lath and nearly at right angles to the strands so as to form ledges to support mortar pressed through the space between strands when the strips are horizontal.

3. An expanded metal lath having a plurality of rows of herring-bone construction, each row having a central strip, and longitudinal portions of Z-shaped cross-section, the flanges of said Z-shaped portion forming 80 ends for the strands, said strips and flanges lying in substantially parallel planes at an angle to the plane of the lath, and nearly at right angles to the strands, said rows being separated by longitudinal portions, so as to form ledges to support mortar pressed through the space between strands when the strips are horizontal, the edge strips at the edges of each longitudinal portion being 85 nearly at right angles thereto.

4. An expanded metal lath having a plurality of rows of herring-bone construction, each row having a central strip and edge strips forming ends for the strands, said strips lying in substantially parallel planes 90 at an angle to the plane of the lath, and nearly at right angles to the strands, said rows being separated by longitudinal portions, so as to form ledges to support mortar pressed through the space between strands when the strips are horizontal, the edge strips at the edges of each longitudinal portion being nearly at right angles thereto.

and extending in opposite directions so as to form a Z-shaped section.

5. In an expanded metal lath, a plurality of rows of herring-bone construction, each 5 row having a central strip disposed at an angle to the plane of the strands, a Z-shaped rib parallel to the central strip, the flanges of the Z-rib lying substantially parallel to said central strip and one of said flanges 10 and said central strip being integral with the ends of one of the rows of strands.

6. In an expanded metal lath, a plurality of rows of herring-bone construction, each row having a central strip disposed at an angle to the plane of the strands, a Z-shaped 15 rib parallel to the central strip and lying between two of said rows, the flanges of the Z-shaped rib lying substantially parallel to said central strip, and each of said flanges being integral with the ends of one of the 20 rows of strands.

JOHN MANOFSKY.
